L. L. WILLSON.

Improvement in Fanning-Mills.

No. 132,784.

Patented Nov. 5, 1872.

John C. McAlpine, Fig. 11.
Charles McIntyre.

Levi S. Willson.

UNITED STATES PATENT OFFICE.

LEVI L. WILLSON, OF DENMARK, MICHIGAN.

IMPROVEMENT IN FANNING-MILLS.

Specification forming part of Letters Patent No. 132,784, dated November 5, 1872.

To all whom it may concern:

Be it known that I, LEVI L. WILLSON, of Denmark, in the county of Tuscola and State of Michigan, have invented a new and valuable Improvement in Fanning-Mills; and I do hereby declare that the following is a full, clear, and exact description thereof, which will enable others skilled in the art to make and use the same, reference being had to the accompanying drawing forming a part of this specification.

This invention has for its object to furnish an improved arrangement of means or devices greatly increasing the screening capacity and general adaptability of fanning-mills; and consists in the novel construction of certain parts and their combinations, as hereinafter more fully set forth and claimed.

In the drawing, Figure 1 is a vertical longitudinal section, showing also the parts attached to the sides. Fig. 2 is a transverse vertical section of the hopper. Fig. 3 is a detached view, showing the construction of the feed-gate. Fig. 4 is a detailed view of chaffer, showing the upper edge of the shelves and the arrangement of prongs. Fig. 5 is a view of a part of a vibrating lever, showing the slots in which the bearers rest. Fig. 6 is a detail view of the connecting-rods. Fig. 7 is an end view of the guard with part of the upturned edge removed. Fig. 8 is a perpendicular view of that end of the frame of an upper screen which is at the left hand in Fig. 1. Fig. 9 is a view of the rods which support the outer end of the upper screens. Fig. 10 is a view of the rods which support the outer end of the lower screen. Fig. 11 represents a form of the levers C, which may be substituted for the levers C and C', as shown in Fig. 1.

The same letter in different figures refers to the same part in each.

The frame, fan, cog-wheels, &c., may be constructed in any suitable manner.

A represents the hopper. The sides A¹ should extend below the boards A² and A³, which form part of the bottom. On each inner side at a³ a pivot is placed to support the feed-gate; on each outer side, extending along the upper edge, is a cleat, by means of which the hopper rests upon the sides of the mill, and may be adjusted so as to allow the grain to

fall at any desired place. A transverse vertical section is shown in Fig. 2 in which 2 represents the cleats. a represents the feed-gate, which also forms a part of the bottom of the hopper; the upper edge rests upon the pivots a³. It may be adjusted by a set-screw, as shown at 1, Fig. 1, or by a wedge, which may be used in any convenient manner between the handle a¹ and the board A³, as shown by the dotted lines at w, Fig. 1. As the gate a extends under the edge of the board A², the opening formed between them is in the direction of the fans, hence the grain in falling through is thrown against the current of air, and, being heavier than the various substances that are to be winnowed out, a more speedy and perfect separation is effected than is possible when it falls from a slide, which gives it the opposite motion. For chaffing, the feed-gate should be removed. B represents the chaffer. The shelves b may be formed of thin boards, and may be framed into the sides b², or they may be hinged in any suitable manner. The prongs b¹ project from the upper edge of the shelves, as shown in Fig. 4. The upper end of the chaffer is suspended by the rods c; the lower end rests upon the upper screen, the spurs b³ being placed in holes in the frame of said screen. D indicates a coarse screen; the inner end of the frame is notched at each side to allow it to pass between the vibrating levers, and spikes driven in to form the bearers d, as shown in Fig. 8. D¹ represents a fine screen, also provided with bearers d, as in Fig. 8. D² represents the lower fine screen, provided with a guard which throws off the screenings that fall through D¹, over each side, into the drawer J. E represents a guard; it may be made of sheet iron, and should be bent lengthwise, so that each side will slope downward from the center, as shown in Fig. 7; the edge should be turned up at each end sufficiently to prevent the screenings from the upper screen from falling off before reaching the sides. The up-turned edge is shown at e, and is partly broken away in Fig. 7. The sides should be incised, as indicated at e', so as to slide partially under the screw-heads or other support provided in the screen to which it is attached. By placing a guard on the screen D¹ and elevating the

screen D, an additional fine screen may be used, from which the grain will fall upon the upper end of the screen D¹; thus, by increasing the number of guards, any desired number of fine screens may be used. The upper screens are supported and adjusted at the outer end by the rods c, which are suspended from the plates c¹, as shown in Figs. 1 and 9, and vibrate with the screens. The lower screen is supported and adjusted at the outer end by the rods c², which are attached to the plates c¹, as shown in Figs. 1 and 10, and also vibrate with the screen. The inner end of the screens is supported by levers, constructed and arranged to support and vibrate the screens in opposite directions, and also afford bearings for their vertical adjustment. For this purpose the levers C, provided with bearings, as shown at 3 in Figs. 1, 5, and 11, may be used, being attached to the frame at S², and to the connecting-rods at t. The levers C may also be used in connection with levers C¹, in which case the levers C and C¹ are attached to the frame at S and S¹, and to each other at t', the connecting-rods being attached at t, as before. F represents a slide-board, used to turn the grain from D¹ forward onto D². When more than one set of fine screens are used, one or more additional slide-boards will be required. The direction of the blast may be regulated by boards placed in a suitable manner above and below the fans. H is the connecting-rods. I is the pinion, which is also a crank-wheel. The pinion is attached to the end of the axle that carries the fans, and to the opposite end a second crank-wheel, I', is attached. The crank-wheel should have a number of holes at different distances from the center, but exactly corresponding in each, that the desired vibration may be secured by attaching the connecting-rods at that distance from the center which will secure the same. m is a board extending across the frame that prevents the air from escaping upward when the hopper is drawn further from the fan. The chaffer and screens,

being held in place by their weight only, may be loosened and removed by simply raising them from their position.

In operating the mill the power is applied by a crank or other means to the driving-wheel, which meshes into the pinion. The grain falls from the hopper to the chaffer, (when it is used,) then slides on the shelves toward the fan, and falls onto and through the coarse screen, thence over all the fine screens, the screenings being turned over the sides into the screen-box by the guard or guards, and falls from the mill at z.

Having thus described my invention, what I claim as new, and desire to secure by Letters Patent, is—

1. The hopper A of a fanning-mill, provided with cleats 2 2, so as to be capable of longitudinal adjustment, and with the feed-gate a, swinging on pivots a³, and adjusted by setscrew 1 or wedge w, substantially as herein described.

2. The chaffer B of a fanning-mill, constructed as described, and provided with the prongs b¹, substantially as set forth.

3. The levers C, provided with slots 3, as described, and arranged to vibrate the screens while affording bearings for their vertical adjustment, substantially as herein described.

4. In combination with the screens of a fanning-mill the vibrating levers C and the rods c, arranged and connected so that the screens can be adjusted vertically by them at either or both ends, substantially as described and set forth.

5. In combination with a screen of a fanning-mill the guard-plate E, substantially as set forth.

6. The combination of the levers C and C¹, screens D, D¹, and D², chaffer B, rods c, slide F, and connecting-rods H, substantially as and for the purpose hereinbefore set forth.

LEVI L. WILLSON.
